CLAIM

The ornamental design for a winged wire connector, as shown and described.

DESCRIPTION

FIG. 1 is a perspective view of the connector from the sides, the view from the other side being identical; FIG. 2 is a plan view of the connector from the side showing one side face of each of the wings, the view from the other side being identical;

FIG. 3 is a plan view of the connector from the side showing the edge of one of the wings, the view from the other side being identical;

FIG. 4 is a top view of the connector; and,

FIG. 5 is a bottom view of the connector.

FIG.1.

FIG.2.

FIG.3.

FIG.4.

FIG.5.

UNITED STATES PATENT AND TRADEMARK OFFICE
CERTIFICATE OF CORRECTION

PATENT NO. : Des. 339,106
DATED : September 7, 1993
INVENTOR(S) : McLaughlin et al

It is certified that error appears in the above-identified patent and that said Letters Patent is hereby corrected as shown below:

On the title page: Item [30] Foreign Priority "200192" should be --20019213 --.

Signed and Sealed this

Twenty-second Day of March, 1994

Attest:

BRUCE LEHMAN

Attesting Officer

Commissioner of Patents and Trademarks
